UNITED STATES PATENT OFFICE.

WILLIAM H. WINSLOW, OF CHICAGO, ILLINOIS.

DESIGN FOR A PRISM-PLATE FOR WINDOWS.

SPECIFICATION forming part of Design No. 26,864, dated April 6, 1897.

Application filed February 9, 1897. Serial No. 622,675. Term of patent 14 years.

To all whom it may concern:

Be it known that I, WILLIAM H. WINSLOW, a citizen of the United States, residing at Chicago, in the county of Cook and State of Illinois, have invented a certain new and useful Design for Ornamental Prism-Plates for Windows, of which the following is a description.

My invention relates to a new design for ornamental prism-plates for windows and is illustrated in the accompanying drawings, wherein—

Figure 1 is a face view of a portion of a prism-plate embodying my design. Fig. 2 is a section.

Like letters refer to like parts throughout both figures.

The design consists of a series of prism-lights A A, provided each with the substantially parallel projecting prisms B B, separated by grooves or indentations C C. A number of these prism-lights are placed near

together, being separated by the thin strips D D' of opaque material. The opaque strips D', which are placed substantially at right angles to the projecting prisms, are provided with the enlargements D², said enlargements being located at intervals along their lengths and in the grooves or indentations between the prisms.

The essential feature of my design is the series of prism-lights provided with substantially parallel projecting prisms separated by thin strips of opaque material, as shown.

I claim—

The design for ornamental prism-plates for windows, substantially as shown and described.

WILLIAM H. WINSLOW.

Witnesses:

FRANCIS W. PARKER,
DONALD M. CARTER.
